UNITED STATES PATENT OFFICE

JOHANNES RIEDER, OF VOHWINKEL, GERMANY, ASSIGNOR TO COSMAN VILLBRANDT & ZEHNDER A. G., OF ELBERFELD, GERMANY, A COMPANY OF GERMANY

BRAID AND LIKE WINDER

Application filed June 27, 1930, Serial No. 464,359, and in Germany July 10, 1929.

This invention relates to a machine for winding braid or the like on cards or the like and of the kind wherein the feeding of the cards into the holders, the attachment of the braid to the card, the rotation of the latter for winding the braid, the cutting of the braid, and the delivery of the wound card, are automatically effected.

The invention consists essentially in arranging the braid clamps and the shears for cutting the braid directly on the card holders, the object being to obtain, within very narrow limits, a correctly measured length of braid on each card.

Means are also provided for feeding the braid so as to place the last but one convolution in a diagonal position on the card as well as means for pulling said diagonal convolution over the severed end of the braid so as to retain it in position.

Fig. 1 of the accompanying drawings represents a vertical section of the left half of the machine,

Fig. 2 is a corresponding section of the right half of the machine.

Fig. 3 is a top view of the card holders.

Fig. 4 is a section on the line IV—IV of Fig. 1, seen in the direction of the arrow 1,

Fig. 5 is a front view of the card magazine, 30 and

Fig. 6 is a section on the line VI—VI of Fig. 1, seen in the direction of the arrow 2.

The machine comprises three upright casings 1, 3 and 5 the two latter of which are mounted on and adjustable along an elongated bed frame 2. The casing 1 is secured to one end of the frame 2 and carries one of the operating spindles 20, the other operating spindle 6 being mounted in the casing 5 in alignment with the spindles 20. The casing 3 serves as a magazine for the cards or the like whereon the material is to be wound and it is laterally offset on the frame 2 and from the spindles, as shown in Fig. 6. The cards

45 are stacked in the magazine 3 and supported in the latter by a plate 11 which is carried by a cylindrical plunger 112 having weight reducing apertures 114. A spring 115 surrounds the latter and exerts upward pressure on the plate 11 so as to press the cards

against a slide 53 which covers the top of the magazine and which moves under a rigid guide plate 52.

Mounted on the adjacent ends of the spindles 6 and 20 opposite the card magazine, 55 are two card holders 61 and 78 respectively. The slide 53 is reciprocated periodically and has a shoulder whereby the top card is engaged and pushed into slits in the holders 61

and 78 while the latter are at rest and while 60 the slits are in a horizontal position and in alignment with the slide. The spindles are fitted with pinions 22 which mesh with gear wheels 21 on a shaft 19 and receive motion from the latter for rotating the spindles. 65 The shaft 19 receives motion from a shaft 13 through the medium of spur gears 16, 17 and 18, the gear 17 being an idle gear and mounted on a pivoted bracket 23 (Fig. 6) allowing the gear 16 to be exchanged for varying the ratio of the transmission. The shaft 13 carries a Maltese-cross 14 which co-operates with a pin wheel 12 for rotating the shaft, the pin wheel being mounted on a shaft 11 which is rotated by a worm gear 9, 10. 70

The worm shaft receives motion from a suitable motor through the medium of speed reducing gears 7 and 8. The pin wheel 12 is continuously rotated and drives the shaft 13 and the spindles only during twelve fifteenths of each revolution. During the remainder of its revolution it engages the Maltese-cross with a segment 15 and maintains the spindles with the card holding slits in the horizontal position shown in Fig. 1. 80

In order to allow the stationary position of the card holders to be rectified after a change of gears, the pinion 18 is connected to its shaft 19 through the medium of a flange coupling 108, 110 (Fig. 2) and screw bolts 90 85 109, the latter being passed through segmental slots in the flanges so as to allow the shaft to be rotatably adjusted relative to the pinion.

The braid or the like is fed to the cards 95 through a traverse guide 88 mounted on a slideable shaft 91 (Fig. 6). The cover plate 90 of the guide restricts the passage through the latter for breaking purposes, and the plate can be adjusted for various thicknesses of 100a

braiding by means of screws 92 which bear against an arm 89 connected to the plate.

Before the braid reaches the guide 88, it passes between a roller 93 and a rod 94 which latter is connected to a frame 96 arranged 5 to turn about the shaft 75 of the roller. The frame 96 controls a stop motion which comes into operation in case the braid should carry knots unable to pass through the guide. For 10 this purpose the driving gear 8 is coupled to its shaft through the medium of clutch elements 106 and 107 the former of which is slidably feathered on the shaft and controlled by a lever 105 mounted on a shaft 104. 15 An arm 103 on the latter shaft is connected by a rod 102 to a lever 101 mounted on a shaft 97. A spring 99 exerts a pull on an arm 98 mounted on the shaft 97 and tends to de-clutch the driving gear 8. This is normally 20 prevented by an arm 100 which is also mounted on the shaft 97 and which bears normally against the frame 96. In case the braid should be knotted, the knots will be engaged between the rod 94 and the roller 93 and turn 25 the frame 96 so as to withdraw the support from the arm 100. The spring 99 can then act so as to stop the machine. The lever 101 is fitted with a handle whereby the mechanism 30 can be restored to the normal position.

The guide plate 52 for the card feeding slide 53 is provided with brackets wherein the shafts 91, 95 and 97 are supported. The structure is connected pivotally to the magazine and is held in position by a locking rod 116 after the withdrawal of which the structure 35 can be tilted in order to allow the magazine to be replenished with cards.

The card holder 78 is provided with means for clamping the card to the holder and also for clamping the starting end of the braid to the card. Such means comprise a slide 79 mounted on the holder so as to be rotated together with the latter, and a wedge-shaped collar 76 which also rotates together with the holder and which is connected to the slide 45 by means of a coil spring 77. A double-armed lever 80, mounted on the slide and controlled by a spring 83, carries a fork provided with abutments 82 adapted to be applied to the card 4 so as to clamp it to the holder and retain it in position. The lever also carries 50 a resilient finger 81 which is adapted to clamp the starting end of the braid against the card while the latter is engaged by the abutments 82. The collar 76 is controlled by lever 75 55 which, on being operated, first advances the slide and the lever into operative position, and then, while compressing the spring 77, engages the lever 80 with its bevelled surface 60 and turns the lever in opposition to the spring 83 so as to apply the finger 81 to the braid and the abutments 82 to the card.

A similar arrangement of slide and collar is to be found on the card holder 61. In this case the slide 65 is fitted with a pair of shears

for cutting the braid after the winding of the card. One member 62 of the shears is rigidly connected to the slide, the other member 63 being pivoted to the slide and connected to an arm 117 together with which it 70 forms a double-armed lever. The wedge-shaped collar 59 advances the slide for operation through the medium of a spring 60 and then, while compressing the spring, engages the lever 117 and turns it so as to operate the 75 shears. The lever also carries a resilient clamping finger 64 which, before the shears are operated, engages the braid so as to retain the severed end thereof on the card. The collar 59 carries a hook-ended rod 66 the hook of which is first advanced by the collar and then retracted for pulling one of the braid convolutions over the severed end of the braid. Spring controlled pins 67 and 68 80 are employed in combination with a cam 118 for retaining the shears and the finger 66 in operative position, against the action of a spring 69, until the finger has been withdrawn from under the braid convolution pulled over it by the hook 66.

The collars 59 and 76, the traversed mechanism and the card feeding slide 53 are operated by cams connected to a drum 28, the latter being secured to the shaft 11. The cams 24, 25, 26 and 27 co-operate with levers 33, 35, 34 and 36 respectively which are mounted on shafts 29, 31, 30 and 32 and which engage 95 collars 22 on rods 37, 38, 39 and 40 respectively so as to reciprocate the latter in co-operation with springs 41.

The rod 37 is fitted with collars 42a whereby it controls a lever 43 and operates, by means of the latter in combination with a hollow shaft 44 and a pair of conical gear segments 45 and 46, a rock shaft 47. The latter transmits motion by means of conical gear segments 48 and 49 to a rock shaft 50 which is mounted on the rear wall of the magazine 3 and which is fitted with a lever arm 51. The latter controls the slide 53 and is operated at the right moment for feeding a fresh card into the holders and ejecting the old one.

The rod 38 is fitted with collars 42b whereby it controls a lever 54 mounted on a vertical shaft 55 and operates by means of the latter 115 and by means of conical gear segments 56 and 57 a forked lever arm which controls the collar 59.

The rod 39 is fitted with collars 42c whereby it controls a lever 70 mounted on a vertical shaft 71 passing through the hollow shaft 44, and operates by means of said shaft 71 and by means of conical gear segments 72 and 73 a rock shaft 74, the latter being fitted 120 with a forked lever arm 75 which controls the collar 76.

The rod 40 is fitted with collars 42d whereby it controls a lever arm 84 mounted on an inclined rock shaft 85. Another lever arm 125

86 on the latter shaft engages the traverse guide 88 and reciprocates the latter.

The action is as follows:

While the card holders are maintained by the segment 15 and the Maltese-cross 14 with the card slits in the horizontal position as indicated in the drawings, and while the slide 79 is retracted by the cam 26, the slide 53 is operated for feeding a card 4 from the magazine 3 into the slits in the card holders 61 and 78. When the card is in position in the holders, the rod 39 is released by the cam 25, and the slide 79 is then advanced, and the lever 80 is operated by the collar 76 so as to apply the finger 81 to the end of the braid and the abutment 82 to the card for securing both in position. Thereupon the Maltese-cross 14 is engaged in succession by the pins of the wheel 12 and rotated by driving the spindles and winding the braid on the card, the traverse guide 88 being meanwhile operated by the cam 27 for distributing the braid convolutions over the card. During the last but one revolution of the spindles, the traverse guide makes a rapid movement towards the card holder 61 so as to lay the braid diagonally across the card. After the last revolution of the card holders they are again stopped with the slits in a horizontal position, and the shears are thereupon advanced for cutting the braid. Before the shears are operated for cutting the braid, the latter is secured by the finger 64. As the collar 59 is retracted after the cutting of the braid, the hook 66 engages the diagonally laid braid portion and pulls it over the severed end of the braid so as to secure the latter in position. Meanwhile the finger 64 is retracted from under the braid portion pulled across it. It is then raised and the shears are opened and retracted. The slide 79 is now retracted by the cam 26 so as to release the finger 81 from the braid and the card from the abutments 82 whereupon the slide 53 is operated so as to supply a fresh card which, on entering the slits, pushes the old card out of the holders on to a delivery chute 119. Meanwhile the traverse guide is shifted over towards the card holder 78 so that, on the slide 79 being restored by the cam 26 for securing the fresh card, the end of the braid can be caught by the finger 81. Thereupon the operation is repeated.

The number of braid convolutions and thus the length of braid wound on the card may be varied according to the thickness of the material and to requirements. In the arrangement shown, the gears 21 rotate the spindles at the ratio of 6:1 while the Maltese-cross receives motion from the pin wheel 12 at a ratio of 3:1. The ratio between the gears 16 and 18 can be varied from 1:1 to 3:1, which allows the winding of the cards to be varied from 18 to 54 convolutions.

65 The casing 5 can be adjusted along the bed

frame 2 and along the shafts and the rods for admitting larger cards, and the casing 3 can also be adjusted and exchanged. The cam 27 is exchangeable for varying the extent of the traverse movement according to requirements. The bed frame, the shafts and the rods may be made long enough to take a plurality of sets of winding mechanisms all of which may be controlled from the same cams.

I claim:

1. A machine of the character described for winding braid and the like on cards and the like, comprising a pair of co-operating holders adapted to hold a card between them, means for rotating the holders periodically, means for feeding cards into the holders while the latter are at rest, means for feeding braid to the rotating card, and means carried on said holders for clamping the starting end of the braid to the card, for cutting the braid after the winding, for retaining the severed end, and for pulling one of the braid convolutions over the severed end.

2. The machine claimed in claim 1 in combination with means on said holders for clamping the card to the latter.

3. A machine of the character described for winding braid and the like on cards and the like, comprising a pair of co-axial spindles, card holders arranged on the adjacent ends of the spindles and adapted to hold a card between them, means for rotating the spindles periodically, means for feeding cards into the holders when the latter are at rest, a traverse guide for feeding braid to the rotating card, slides on said holders, means for reciprocating said slides, clamping members on the slide of one holder adapted, in one position of the slide, to engage the card and the starting end of the braid for holding them in position, shears carried by the slide on the other holder, means for operating said shears in one position of the slide so as to cut the braid when the card has been wound, and means on said latter slide for retaining the severed end of the braid.

4. A machine as claimed in claim 3 wherein the means for reciprocating the slides and operating the clamping members and the shears comprise wedge-shaped collars arranged on the spindles so as to be axially displaceable thereon, springs transmitting motion between the collars and the slides, means for operating the collars, and levers controlling the clamping members and the shears and arranged so as to be rocked by said collars when the latter are displaced relative to the slides.

5. A machine as claimed in claim 3 wherein the means for reciprocating the slides and operating the clamping members and the shears comprise wedge-shaped collars arranged on the spindles so as to be axially displaceable thereon, springs transmitting mo-

tion between the collars and the slides, cams for operating the collars, levers controlling the clamping members and the shears and arranged so as to be rocked by said collars when the latter are displaced relative to the slides, means for moving the traverse guide so as to place the last but one convolution of the braid diagonally across the card, and a hook connected to one of said collars, said hook adapted to engage the diagonal convolution of the braid and pull it over the end of the braid after the latter has been severed by the shears.

6. A machine as claimed in claim 3 wherein the traverse guide comprises a reciprocating guide member and a brake member co-operating with said guide member, said brake member being adjustable for use with different thicknesses of braid.
